CLAIM

The ornamental design for orthopedic splint, as shown and described.

DESCRIPTION

FIG. 1 is a side perspective view of an orthopedic splint according to this invention, shown as typically worn on a patient's wrist drawn in phantom lining;

FIG. 2 is a front view thereof, shown with straps wrapped about the splint;

FIG. 3 is a top end view thereof;

FIG. 4 is a right side view thereof;

FIG. 5 is a left side view thereof;

FIG. 6 is a rear view thereof;

FIG. 7 is a bottom end view thereof;

FIG. 8 is a perspective view thereof shown with straps laid flat;

FIG. 9 is a front view thereof;

FIG. 10 is a top end view thereof;

FIG. 11 is a right side view thereof;

FIG. 12 is a left side view thereof;

FIG. 13 is a rear view thereof;

FIG. 14 is a bottom end view thereof; and,

FIG. 15 is an exploded perspective view thereof with detached straps.

The broken line showing of an arm and hand in FIG. 1 is included for the purpose of illustrating environmental structure and forms no part of the claimed design.
